SHAVING APPARATUS

George H. Robertson, Bellerose, N. Y., assignor to
 The Roto-Shaver, Inc., New York, N. Y., a corporation of Connecticut

Application March 15, 1950, Serial No. 149,783

9 Claims. (Cl. 30—43)

1

This invention relates to shaving apparatus, and has particular reference to shaving apparatus of the type in which a rotary cutter traverses the underside of a perforate shear plate about an axis disposed normal thereto.

Shaving apparatus of the general type described utilize a shear plate having a convex configuration giving the shear plate the self-sustaining property so as to enable it to withstand shaving pressure without flexing and the capacity to restore itself to shape when flexed, while at the same time enabling the shear plate to have the thinness essential to provide a close shave. Because of its shape the convex shear plate has a limited effective shaving area, as compared to a flat shear plate, but because of the inherent weakness of a flat surface having the thinness necessary to a close shave, the flat shear plate heretofore has been confined to the narrow shavers of the reciprocating type and even there it has been acknowledged that support against the flexing caused by the shaving pressure is necessary, as is indicated in Patent No. 1,721,530, for example.

In accordance with the present invention, a flat shear plate shaving apparatus of the large area rotary type is provided, in which the inherent weakness of a flat shear plate of large area having the thinness necessary for close shaving is compensated for by supporting it against material flexing and restoring its flat shape when flexed during use, so that the shaving advantages of a flat shear plate are obtained and maintained.

In a preferred embodiment of the invention, a flat, thin, perforate shear plate is traversed on its under surface by two or more blades rotated about an axis substantially normal to the shear plate and so constructed and arranged as to exert a continuous counter-pressure against the underside of the shear plate on the order of the pressure with which the shear plate is pressed against the skin during the shaving operation. This counter-pressure of the blades against the shear plate is derived from the centrifugal force of rotation of the cutter member carrying the blades and is provided at the proper magnitude by mounting and arranging the center of gravity of rotating parts so as to produce that force in the right direction.

It will be seen that the shaving apparatus of this invention realizes in a practical and effective way the desirable large area shaving surface provided by a flat shear plate of the desired thinness.

For a more complete understanding, reference

2

may be had to the accompanying drawings, in which:

Figure 1 is a plan view of the shaving apparatus of the invention, with the center part of the shear plate shown broken away to illustrate the construction of the centrifugal blade holders;

Fig. 2 is a section taken in a plane parallel and adjacent to the axis of rotation of the blade holder, as seen along the line 2—2 of Fig. 1; and

Fig. 3 is an enlarged transverse section through the blade holder and blade, as seen along the line 3—3 of Fig. 2.

Referring to the drawings, numeral 10 generally designates a frame or handle of any desired size and configuration and containing the electric motor whose shaft 11 projects through the upper end of the handle, as shown in Fig. 2. Frame or handle 10 has the peripheral flange 12 to which the head 20 is removably connected as by a bayonet type of coupling described more particularly in Patent No. 2,280,836, for example.

The head 20 comprises the tubular collar 21 which is closed at its outer end by the thin, flat, perforate shear plate 22 and secured to the collar 21 in any suitable way as by peening over it a thin flange of the collar 21, as indicated at 23 in Fig. 2. The shear plate 22 has the general characteristics of the shear plate described in said Patent No. 2,280,836 in that it is thin, on the order of a few thousandths of an inch, so as to afford a close shave, and is pierced with closely-spaced perforations on the order of .025 inch in diameter, but instead of being convex,

the shear plate 22 is flat or plane, as shown especially in Fig. 2. Because of its extreme thinness, the flat shear plate 22 has no inherent shape-retaining or restoring property and, when applied to the skin with normal shaving pressure on the order of three-quarters of a pound per square inch, it will flex and is not inherently capable of rapidly recovering its flat shape without aid.

Secured to the projecting end of motor shaft 11 by means of a set screw 24 or equivalent fastening means, is the blade support or rotor of the shaver which includes the center stem 25 having a socket for the reception of the motor shaft 11 and extending upwardly to a point close to the under surface of the shear plate 22 so as to support the center thereof against flexing. Preferably, the upper end of the shaft portion 26 of the stem 25 is provided with a recess for the reception of a separate supporting button 27 illustrated and described in the aforesaid Patent

No. 2,280,836 as affording the said support for the center of the shear plate 22.

The opposite sides of the stem 26 are flattened and the stem 26 is fitted with a pin 28 extending therethrough and serving as a pivot for a pair of oppositely-extending blade holders 29 and 30, as best shown in Fig. 1.

Each blade holder 29, 30, preferably is formed of a sheet metal stamping comprising a channel-shaped body portion 31, best shown in Fig. 3, having parallel lugs 32 and 33 at one edge by means of which the corresponding holder is pivoted on pin 28. The lugs 32 and 33 are positioned opposite the upper edge of the corresponding holder, and lug 32 is offset laterally from the lug 33, and the latter is an extension of the trailing edge of the channel 31 as shown in Fig. 1. Accordingly, as the blade-holding arms 29 and 30 are rotated in the direction of the arrow in Fig. 1, the lug 32 leads, and the lug 33 follows an axial plane parallel to each. Also, the leading flange of the blade holder channel 31 to which lug 32 is connected, lies approximately in the said axial plane. Accordingly, the blade holders 29 and 30 hold the corresponding blades 35 in such a position as to give the raking cut described in said Patent No. 2,280,836, with its attendant advantages.

Referring to the sectional view of the channel 31 of each of the blade holders 29 and 30, it will be observed in Fig. 3 that the channel is V-shaped and the blade 35 tilts in a direction opposite to the direction of its movement within the limits of the channel 31 so as to continuously present the sharp edge to the hairs projecting through the perforations in the shear plate when the blade 35 traverses the underside thereof in the position shown in Fig. 3. Also, the blade 35 is self-honing, as will be readily understood. This lean back blade feature of construction and operation form no part of the present invention, being disclosed by said Patent No. 2,280,836.

Instead of resting on the bottom of the channel 31, the blade 35 rests on a pin 36 extending across the blade slot 37 of the channel 31 so that the lower edge of the blade is spaced slightly above the bottom of the channel, as shown in Fig. 2. The hole 38 in the blade 35 is oversized, so that the blade is free to tilt backwardly in response to the frictional drag against the underside of the shear plate 32, so that it may assume the position shown in Fig. 3.

When the shaver is not in operation, the blade holders 29 and 30 drop downwardly by gravity about their pivot pin 28 until the heel 39 of the corresponding blade holder rests against the spacing bead 40 on the stem 26, so that the blade 35 is disengaged from the underside of the shear plate, as is indicated by the dotted lines in Fig. 2. When the shaver is placed into operation, the low center of gravity of each blade holder 29, 30, being located at a point G approximately directly below the center of the pivot pin 36 for the corresponding blades 35, the centrifugal force of rotation causes the center of gravity G to tend to move upwardly into alignment with the axis of pivot pin 28. The movement of the blade holders 29 and 30 in this upward direction about pin 28 is limited by the shear plate 22 against which blade 35 is stopped, so that blade 35 traverses the underside of the shear plate in the direction shown by the arrows in Figs. 1 and 3 to shear hairs projecting through the perforations of the shear plate 22.

By reason of the eccentric position of the center of gravity G of each of the blade holders

29 and 30 below the plane of the pivot pin 28 and displaced laterally therefrom, the blades 35 are pressed against the underside of the shear plate 22 with a considerable pressure, at least on the order of the pressure with which the shear plate 22 is normally placed against the skin, namely, on the order of three-quarters of a pound per square inch. Preferably, the counter-pressure of the blades 35 due to the eccentric position of the centers of gravity G of the blade holders 29 and 30 is somewhat greater than the normal shaving pressure to immediately compensate for any exceptional pressures which might cause the shear plate to be distorted momentarily. However, the counter-pressure of the blades should not be so great as to create a disproportionately high drag load on the motor or to create frictional heat. These conditions can be made by selection of the proper weights and lever arms for the blade holders 29 and 30.

The slight spacing of the bottom edge of the blade 35 above the bottom of the channel 31 permits blade 35 to tilt laterally to a limited degree about the axis provided by the pivot pin 36 so that the blade 35 accommodates the relative angular disposition of the blade holders 29 and 30 so as to be always in linear contact throughout its length with the shear plate 22 without, however, being free to tilt sufficiently to tear the shear plate in response to a temporary deformity of the shear plate under shaving pressure. By positioning the pivot pin 36 for each blade 35 approximately in axial line with the center of gravity G, the blade is balanced and may pivot in either direction about pin 36 to accommodate itself to the conditions of operations and to remain sharp at all times.

It will be observed that when the shaver is at rest, heel 39 of each blade holder 29 and 30 rests against the bead 40 so that the blades 35 are disengaged from the shear plate 22. Accordingly, there is no starting load on the motor and the blade holders 29 and 30 do not swing upwardly to press the corresponding blades 35 against the shear plate 32 until a predetermined speed is attained, and thereafter, the pressure increases to that provided by maximum speed of rotation of the blade holders. This pressure does not exceed the predetermined point, and immediately decreases as the motor is shut off inasmuch as the blade holders 29 and 30 drop away from the shear plate to the point where their heels 39 engage the bead 40. By adjusting the weights of the blade holders 29 and 30 and the lever arm from the center of rotation to the center of gravity G or the speed of the motor, the pressure of the blades against the underside of the shear plate may be varied to suit requirements. For example, if a convex shear plate of extraordinary thinness is desired, part of its strength may be obtained by its convex shape as in said Patent No. 2,280,836, and may be augmented by the pressure of the blades against its underside in accordance with the present invention. The same effect would be obtained were a wide angle conical shear plate desired instead of the flat shear plate.

A simple way to adjust the weight of the blade holders is to substitute pins 36 with different weights, such as pins having different sized heads 36'.

In order to provide for ready expulsion of the cut hairs dropping into the blade holding channels 37, the channels 31 are pierced along their bottom edges by slots 41, through which the hair 75 may fall, aided by air flowing through holes 42.

in the leading face of the channels 29 and 30 as shown in Figs. 1 and 3. Also, the centrifugal force expels hair outwardly through channels 31, whose ends 43 are tapered downwardly to permit freedom of centrifugal hair expulsion and also to reduce tip windage, although the holders 29 and 30 may be made any desired shape to suit requirements. The hair collects in the space between head 20 and the casing 10 and may be removed by disengaging the former from the latter.

Operation of the new shaving apparatus of this invention will be readily understood from the foregoing description of the parts of which it is composed, and their functions. It affords a flat shear plate shaving device with all its advantages, but without the disadvantages of instability under shaving pressure, which the counter-pressure provided by the blades having the effect of lending to a very thin shear plate a stiffness otherwise obtained only by making the shear plate too thick to provide the desired close shave. The counter-pressure is applied only during shaving, and hence, does not impose a continuous static load on the motor.

Although a preferred embodiment of the invention has been illustrated and described herein, it is to be understood that the invention is not limited thereby, but is susceptible of changes in form and detail within the scope of the appended claims.

I claim:

1. In shaving apparatus, the combination of a thin perforate shear plate adapted to engage the skin, a drive shaft rotating about an axis substantially normal to said shear plate, a pivot on said shaft extending substantially normal to said axis and positioned adjacent said shear plate, a blade holder mounted on said pivot and having its center of gravity spaced a substantial distance from said shear plate, and a blade mounted on said blade holder and adapted to be moved into wiping engagement with said shear plate by the blade holder in response to centrifugal force upon rotation of said shaft.

2. In shaving apparatus, the combination of a thin perforate shear plate adapted to engage the skin, a drive shaft rotating about an axis substantially normal to said shear plate, a pivot on said shaft extending substantially normal to said axis and positioned adjacent said shear plate, a channel-shaped blade holder mounted on said pivot and having its center of gravity spaced a substantial distance from said shear plate, and a blade mounted in the channel of said blade holder and adapted to be moved into wiping engagement with said shear plate by the blade holder in response to centrifugal force upon rotation of said shaft.

3. In shaving apparatus, the combination of a thin perforate shear plate adapted to engage the skin, a drive shaft rotating about an axis substantially normal to said shear plate, a pivot on said shaft extending substantially normal to said axis and positioned adjacent said shear plate, a blade holder mounted on said pivot and having its center of gravity spaced a substantial distance from said shear plate, stop means normally holding said blade holder close to said shear plate when the shaft is at rest, and a blade mounted on said blade holder and adapted to be moved into wiping engagement with said shear plate by the blade holder in response to centrifugal force upon rotation of said shaft.

4. In shaving apparatus, the combination of a thin perforate shear plate adapted to engage the

skin, a drive shaft rotating about an axis substantially normal to said shear plate, a pivot on said shaft extending substantially normal to said axis and positioned adjacent said shear plate, a blade holder mounted on said pivot and having its center of gravity spaced a substantial distance from said shear plate, and a blade pivoted about an axis substantially parallel to said pivot and lying in a plane parallel to said axis and including the said center of gravity of said blade holder and adapted to be moved into wiping engagement with said shear plate by the blade holder in response to centrifugal force upon rotation of said shaft.

5. In shaving apparatus, the combination of a thin perforate shear plate having a surface of revolution adapted to engage the skin, a drive shaft rotating about an axis including the center of revolution of said shear plate, a pivot on said shaft extending substantially normal to and including said axis and positioned adjacent said shear plate, a blade holder mounted on said pivot and having its center of gravity spaced a substantial distance from said shear plate, and a blade mounted on said blade holder and adapted to be moved into wiping engagement with said shear plate by the blade holder in response to centrifugal force upon rotation of said shaft.

6. In shaving apparatus, the combination of a thin, flat, perforate shear plate adapted to engage the skin, a drive shaft rotating about an axis substantially normal to said shear plate, a pivot on said shaft extending substantially normal to said axis and positioned adjacent said shear plate, a blade holder of substantial mass mounted on said pivot and having its center of gravity spaced a substantial distance from said shear plate, and a blade mounted on said blade holder, whereby the blade holder urges said blade into engagement with said shear plate in response to centrifugal force with sufficient force to substantially counteract the shear plate deflecting pressure of the latter against the skin in use.

7. In shaving apparatus, the combination of a thin, flat, perforate shear plate adapted to engage the skin, a drive shaft rotating about an axis substantially normal to said shear plate, a pivot on said shaft extending substantially normal to said axis and positioned adjacent said shear plate, a plurality of blade holders of substantial mass mounted on said pivot and each having its center of gravity spaced a substantial distance from said shear plate, and a blade mounted on said blade holder, whereby the blade holder urges each blade into engagement with said shear plate in response to centrifugal force with sufficient force to substantially counteract the shear plate deflecting pressure of the latter against the skin in use.

8. In shaving apparatus, the combination of a thin perforate shear plate adapted to engage the skin, a drive shaft rotating about an axis substantially normal to said shear plate, a pivot on said shaft extending substantially normal to said axis and positioned adjacent said shear plate, a blade holder mounted on said pivot and having its center of gravity spaced a substantial distance from said shear plate, a pin on said blade holder and having substantial weight for augmenting the effect of centrifugal force on said blade holder, and a blade pivoted on said pin and adapted to be moved into wiping engagement with said shear plate by the blade holder in response to centrifugal force upon rotation of said shaft.

4. In shaving apparatus, the combination of a thin perforate shear plate adapted to engage the skin, a drive shaft rotating about an axis substantially normal to said shear plate, a pivot on said shaft extending substantially normal to said axis and positioned adjacent said shear plate, a blade holder mounted on said pivot and having its center of gravity spaced a substantial distance from said shear plate, a removable pin on said blade holder and having a head of substantial weight for augmenting the effect of centrifugal force on said blade holder, whereby said pin may be replaced by a pin having a head of different weight, and a blade pivoted on said

5
pin and adapted to be moved into wiping engagement with said shear plate by the blade holder in response to centrifugal force upon rotation of said shaft.
